UNITED STATES PATENT OFFICE.

BERNHARD DREYFUS, OF NEW YORK, N. Y.

DESIGN FOR A PENDANT.

SPECIFICATION forming part of Design No. 15,739, dated January 20, 1885.

Application filed November 18, 1884. Term of patent 7 years.

To all whom it may concern:

Be it known that I, BERNHARD DREYFUS, of the city, county, and State of New York, have produced a new and original Design for Pendants, of which the following is a full, clear, and exact description.

Reference is to be had to the accompanying drawing, forming part of this specification, in which a face view of my new design for pendants is shown.

A is an oval or elongated ring or loop having the appearance of spiral stripes. B is a tuft or ball on one end of said ring or loop, and C is an eye or loop on the tuft or ball. E is a suspension-cord, and D is an oval tuft or slung ruff on the end of the said cord, and F is a bead on the lower end of the tuft or ruff.

D. The tuft D, the cord E, and the bead F are all within the ring or loop A.

Having thus described my invention, I claim as new and desire to secure by Letters Patent—

1. The herein-described design for pend-

ants, consisting of an elongated or oval ring or loop, both end parts of which are shaped alike, and a tuft or slung ruff hung in the said loop at one end of the same, substantially as herein shown and described.

2. The herein-described design for pendants, consisting of an elongated or oval ring or loop, both end parts of which are shaped alike, and of an elongated or oval slung ruff or tuft hung in the said loop, and at one end of the same, substantially as herein shown and described.

3. The herein-described design for pend- ants, consisting of an elongated ring having alternate spiral stripes and a tuft within the said elongated ring, substantially as herein shown and described.

BERNHARD DREYFUS.
